DESIGN FOR A KNITTING NEEDLE

Catherine W. Megarry, New York, N. Y.

Application December 23, 1940, Serial No. 97,572

Term of patent 14 years

To all whom it may concern:

Be it known that I, Catherine W. Megarry, a citizen of the United States, residing at New York, in the county of New York and State of New York, have invented a new, original, and ornamental Design for a Knitting Needle, of which the following is a specification, reference being had to the accompanying drawing forming a part thereof, in which:

Fig. 1 is an enlarged perspective view of the knitting needle showing my new design;

Fig. 2 is a section of the knitting needle in perspective taken on lines 2—2 of Fig. 1;

Fig. 3 is an enlarged section showing the upper transparent material and the lower opaque material taken along lines 3—3 of Fig. 4; and

Fig. 4 is an actual size view of the knitting needle.

I claim:

The ornamental design for a knitting needle, as shown.

CATHERINE W. MEGARRY.
